UNITED STATES PATENT OFFICE

GEORGE H. ADAMS, OF HILL, NEW HAMPSHIRE.

KNITTING-MACHINE NEEDLE.

SPECIFICATION forming part of Letters Patent No. 282,029, dated July 31, 1883.

Application filed December 30, 1882. (No model.)

To all whom it may concern:

Be it known that I, GEORGE H. ADAMS, of 5
Hill, in the county of Merrimack and State of
New Hampshire, have invented a new and use-
ful Improvement in Knitting-Machine Needles,
which improvement is fully set forth in the ac-
companying specification.

This invention relates to knitting-machine
needles; and it consists of a novel means, herein-
10 after described, of securing the pivot by which
the latch of the needle is held in its place.

One of the means heretofore employed to piv-
ot the latch to the body of the needle has been
to use a pivot longer than the thickness of the
15 body of the needle, said pivot passing through
the body of the needle and through a hole in
the end of the latch, there being a slot cut in
the needle to receive the latch. The holes in the
needle were countersunk at their outer sides,
20 and the pivot was riveted down, thus forming
heads at either end, which held the pivot in its
place. The difficulty attendant upon this form
of manufacture was that in the severe strain to
which the needles were put in the rapidly-run-
25 ning machines the pivots frequently became
loosened, and the thin edges of the heads pro-
jected above the surrounding surface and
caught the fiber of the yarn, thereby causing in-
jury to the quality of the work, and frequently
30 much damage to the machine itself. In Letters
Patent No. 210,653, granted to myself and Har-
rison Adams, December 10, 1878, is described
a process of manufacture of knitting-machine
needles designed to overcome this difficulty;
35 and the present invention is designed to still
further improve upon the method described
therein.

In the specification of Letters Patent above
referred to is described a needle wherein the
40 pivot that holds the latch is made of a length
shorter than the thickness of the needle, and is
held in its place by a portion of the metal con-
tiguous to the hole containing the pivot being
forced into the hole and over the end of the
45 pivot, thereby securing it in its place. While
this invention overcame the difficulty from the
fiber catching in the raised surface of the rivet
heads, common to the earlier process employed,
it did not possess the advantage derived from

the fact that the pivot also acted as a rivet to 50
hold the sides of the needle from spreading
apart when subjected to undue strain; and the
object of my present invention is to secure the
strengthening feature of a combined pivot and
rivet, and at the same time retain the advan- 55
tage of having the ends of the pivot kept below
the surrounding surface of the body of the
needle.

The drawings accompanying this specifica-
tion will readily show the nature of my inven- 60
tion.

Figure 1 is a perspective view of a finished
needle. Fig. 2 is an enlarged view of the same,
more clearly showing the connection of the
latch with the body of the needle. Fig. 3 is a 65
longitudinal section, showing the slot to re-
ceive the latch, and also the form of the pivot
when it is secured in its place. Fig. 4 shows
the pivot in its place, but before it has been
subjected to the action of the dies that form the 70
heads to secure it in its place.

In the process of manufacture of my improved
needle, the needle is slotted and drilled in the
ordinary manner. The outer ends of the holes
are then enlarged for a considerable depth, as 75
shown in Figs. 3 and 4. The latch is then placed
within the slot *a*, and the pivot *b* is inserted.
The needle is then subjected to the action of
suitable dies, which, as they come together,
seize and compress or upset the metal forming 80
the pivot, and it is not only enlarged at its
ends, as shown at *b*, but it is also enlarged at
the center *b'*, or at that part embraced by the
hole in the latch, and it is thus made to form
a perfect brace to support the needle, either 85
from the spreading or the closing together of its
sides, while the heads of the rivets lie within
the enlarged ends of the holes and below the
surrounding surface, where they can offer no
obstruction to the passage of the yarn. Thus 90
constructed the needle has all of the advan-
tages of those made by either of the methods
heretofore in use, while it is free from the ob-
jections hereinbefore named, and the test of
actual use has demonstrated its practical util- 95
ity.

Having thus fully described the nature and
operation of my invention, what I claim as

new, and desire to secure by Letters Patent,
is—

5 A knitting-machine needle having a latch
and an independent pivot for securing said
latch, said pivot being of a length shorter than
the thickness of the body of the needle, and
having a central enlargement between the
walls of the needle and heads on the exterior

thereof, within the enlarged pivot-holes, where-
by the heads will lie below the surrounding 10
surface of the needle-body, substantially as
shown, and for the purpose set forth.

GEORGE H. ADAMS.
